(57) CLAIM

The ornamental design for a table, as shown and described.

DESCRIPTION

FIG. 1 is a perspective view of a table design showing my new design.

FIG. 2 is a front view of a table.

FIG. 3 is a rear view of a table.

FIG. 4 is a left side view of a table.

FIG. 5 is a right side view of a table.

FIG. 6 is a top view of a table; and,

FIG. 7 is a bottom view of a table.

In the drawings, the broken lines show portions of the table that form no part of the claimed design.
